(57) **CLAIM**

The ornamental design for an insert for media cable scoop as shown and described.

DESCRIPTION

FIG. 1 is a top, front perspective view of an insert for media cable scoop showing the new design;

FIG. 2 is a top view thereof;

FIG. 3 is a front view thereof;

FIG. 4 is a bottom view thereof;

FIG. 5 is a right-side view thereof, the left-side view being a mirror image thereto;

FIG. 6 is a rear view thereof;

FIG. 7 is a top, front perspective view of an alternative embodiment of an insert for media cable scoop showing the new design;

FIG. 8 is a top view thereof;

FIG. 9 is a front view thereof;

FIG. 10 is a bottom view thereof;

FIG. 11 is a right-side view thereof, the left-side view being a mirror image thereto; and,

FIG. 12 is a rear view thereof.

The even-length broken lines in the figures represent portions of the insert for media cable scoop that form no part of the claimed design. The uneven length broken lines define the bounds of the claimed design and form no part thereof.
